UNITED STATES PATENT OFFICE.

RALPH JACKSON, OF ALTRINGHAM, ENGLAND.

CARBURETER.

SPECIFICATION forming part of Letters Patent No. 678,493, dated July 16, 1901.

Application filed March 18, 1901. Serial No. 51,758. (No model.)

To all whom it may concern:

Be it known that I, RALPH JACKSON, a subject of the Queen of Great Britain and Ireland, residing at Moss Lane, Altringham, England, 5 have invented new and useful Improvements in Carbureters, (for which I have applied for patent in Great Britain, No. 6,170, dated April 3, 1900,) of which the following is a specification.

10 This invention relates to apparatus for producing inflammable or explosive vapor or mixture of air and hydrocarbon vapor for use in oil, spirit, or like internal-combustion engines.

15 A carbureter according to the present invention is of the kind wherein such vapor is produced by passing atmospheric air through a textile curtain or its equivalent which holds oil, spirit, or other suitable volatile hydrocarbon liquid in suspension, whereby such air is saturated with the nature of the liquid held by the curtain.

20 In the drawings hereto annexed, Figure 1 is a side elevation, partly in section. Fig. 2 is an end view, and Fig. 3 is a plan, of the apparatus according to this invention. Fig. 4 is a cross-section on line A B, Fig. 2. Fig. 5 is a cross-section on line C D, Fig. 2.

25 Referring to the drawings, it will be seen that carbureting apparatus according to this invention comprises a reservoir or container *a* for the hydrocarbon. In the top of the container *a* are two apertures *b*, closed by caps *c*. Attached to the caps *c* are cylindrical pieces of perforated zinc or other suitable perforated material or wire-gauze *d*. Stitched, bound, or otherwise fastened to the perforated material *d* are circular wicks or absorbent curtains *e*, which reach to a point below 30 the level of the hydrocarbon *f*. Consequently the wicks or absorbent curtains *e* raise the hydrocarbon and hold it in suspension. Passing through the caps *c* are tubes *g*, which pass down within the curtains *e* to a point 35 slightly above the hydrocarbon-level. The upper ends of the tubes *g* possess a packing or diaphragm of wire-gauze *h* and are open to the atmosphere.

40 Mounted in the top of the container *a* is a T-tube *i*, which contains a cylindrical valve *k*. Cut in this valve is a slotted port which

45 opens communication between the vapor-duct *m* and the interior of the valve and also between the air-admission port *n* and the interior of the valve. The valve *k* is operated by the handle *k'*, and upon reference to Fig. 4 it will be seen that by turning this handle to three different positions the following three conditions are effected, namely: the interior of the valve *k* is put in communication with the carbureter only, with the carbureter and the atmosphere, and with the atmosphere only. Attached to the open end of the T-tube *i* is a T-tube *o*, containing a throttle-valve *p*. The branch *q* leads to the combustion-chamber of the engine. The valve *p* possesses one port *p'*, which controls the branch *q*.

50 In operation the air which is permitted to pass down the tubes *g* is drawn by the suction of the engine through the interstices of the wicks or curtains *e* and in its passage absorbs or takes up a quantity of the liquid held thereby and becomes an inflammable vapor. The passage of such vapor to the engine (or elsewhere) is controlled and regulated by the valves *k* and *p*. It will be seen in Fig. 4 that the valve *k* is arranged to supply the engine (or other consumer) with undiluted vapor, vapor and air, or air alone, according to the position to which it is turned. 55 Consequently the precise fuel requirement of the engine may be regulated by the valve alone. Having gaged the requirement of the engine by means of the valve *k*, the control of the engine may be effected by the throttle-valve *p*, thereby obviating any necessity for altering the adjustment of the valve *k*. The valve *p* is operated by the handle *p'*.

55 A float *r* indicates the level of liquid in the container by means of the spindle *r'*, which passes up the tube *g*.

60 *s* is a drain-cock by which surplus hydrocarbon may be withdrawn.

65 Liquid hydrocarbon is admitted to the container by the tube *t*, the supply being automatically controlled by the needle-valve *u*, operated by the float *v*.

70 In the lower part of the container *a* is disposed a coiled pipe *w*, through which may be passed a portion of the engine waste gases 75 when it is required to increase the volatility of the hydrocarbon.

The gauze packing or diaphragms *h h* are for the purpose of silencing the suction of the engine.

It will be seen that one side of the container *a* is indented in order that it may be fitted close to the engine-crank chamber, the carbureter shown being arranged for use upon the motor of a self-propelled carriage.

What I claim as my invention, and desire to secure by Letters Patent, is—

1. A carbureter comprising a reservoir provided with an aperture in its top, a cap removable for closing said aperture having a central opening, a perforated cylinder secured to the cap and projecting into the reservoir, a wick surrounding the perforated cylinder and extending into the reservoir to a point below the liquid-level, a tube within the cylinder secured in the opening in the cap projecting into the reservoir and terminating at its lower end in the perforated cylinder above the liquid-level in the reservoir and at its upper end outside of the cap, a wire-gauze top on said tube, and a vapor-delivery pipe lead-

ing from the top of the reservoir to the point 25 of consumption of the vapor, all combined and operating substantially as and for the purposes set forth.

2. A carbureter comprising a reservoir, carbureting devices therein, a T-shaped vapor-delivery pipe, the stem of which leads from the reservoir, its head being provided with a port opening into the atmosphere in the same transverse plane with the opening to its stem, and a hollow cylindrical valve longitudinally 30 fitted in the said head of the pipe having one end open and provided with a port in the same transverse plane as the air-port and the opening to the stem, the valve-port being adapted to register with either the air-port, 40 or the opening to the stem of the T-pipe, or both simultaneously, substantially as and for the purposes set forth.

RALPH JACKSON.
